UNITED STATES PATENT OFFICE

2,290,469

ELECTRIC CIRCUIT INTERRUPTER OR
BREAKEROtto G. Griesbach, Chicago, Ill., assignor to
Barbara Moore Kight, Chicago, Ill.

Application April 1, 1940, Serial No. 327,128

12 Claims. (Cl. 200—30)

This invention relates generally to new and useful improvements in electrical circuit interrupters or breakers and has particular reference to novel improvements in timers for automobile ignition systems.

One of the objects of my invention resides in the novel assembled unit consisting of a pair of breaker points mounted on a pair of preferably relatively movable resilient arms supported on a single base plate pivotally mounted upon the breaker supporting plate within the breaker casing.

Another object of my invention is found in the provision of a cam-engaging fiber block operatively associated with one of the breaker-point supporting arms and wedge means on the base plate cooperating with a spring-pressed member for automatically adjusting the cam-engaging block relatively to the rotary cam to compensate for wear of such block caused by its repeated contacts with the rotating cam. The automatic adjustment of such cam-engaging fiber block permits assembly of the breaker unit and pre-setting of the breaker points at the factory, and eliminates the usual necessary adjustment of the breaker points by mechanic during installation since the breaker points and their resilient supporting arms are properly set and assembled with the supporting base plate at the factory and therefore such assembled unit may be readily mounted upon the breaker supporting plate and automatically set in operative position by the spring-pressed member without further adjustment of the breaker points.

Another object of my invention resides in the provision of a single base plate for supporting a pair of movable, and preferably relatively movable, flexible breaker-point supporting arms, a single cam-engaging block carried by one of the breaker-point supporting arms, and spring-pressed means for retaining the base plate in practically stationary position while said breaker points are repeatedly moved into make and break positions by the rotating cam.

While the base plate is non-oscillatable at each make and break it is, however, adapted for slight automatic adjustment movement responsive to the wear of the cam-engaging block and the action of the spring-pressed wedge means to thereby compensate for such wear and thus maintain proper timing of the make and break action of the breaker points.

Still another feature of my invention is found in the provision of flexible lightweight breaker-point supporting arms mounted on a common

pivoted non-flexible base plate and additional pressure-balancing springs for the breaker point flexible supporting arms whereby a true flat face to face contact of the breaker points is assured, 5 and the adaptability of such lightweight breaker to high speed operation is made possible by the elimination of objectionable chatter or bounce and the resulting irregular timing and decreased dwell which hinder the proper electrical build-up of the coil.

A further object of my invention resides in the provision of a circuit breaker having a pair of comparatively light-weight flexible breaker-point supporting arms mounted on a common base plate 15 and each of such flexible arms provided with a coil spring resisting flexing of such arms whereby not only uncontrolled oscillations of such light-weight arms are prevented but more perfectly balanced spring pressures are attained 20 through springs of comparatively small tension.

A still further object of my invention is found in the novel construction and arrangement of the cam-engaging block which is provided with a laterally disposed slot or recess constituting a 25 pocket for a grease lubricant. A fiber retainer may be provided at one end of the block to insure retainment of the grease therein, or the retainer may be provided within the block recess.

A still further object of my invention is to 30 provide a timer wherein, due to the simplified construction and mounting of the breaker-pointing supporting arms on a common base plate and the elimination of bushings for the arms, the unit is rendered susceptible to precision 35 manufacture and assembly eliminating play and providing an accurately centered full-face contact of the faces of the points under very small tolerances.

Still another object of my invention is found 40 in the assembly and mounting of the breaker-point carrying arms on a common pivotally mounted base plate, the pivotal center of which is different from that of the arm supporting the cam-engaging block whereby cam angle can be 45 more accurately maintained with a wide cam-engaging block.

With the above and other objects in view, which will become apparent from perusal of the following specifications and attached drawings, my 50 invention consists in the novel combination, construction and arrangement of the parts and members shown in preferred embodiment in the attached drawings, described in the following specifications and particularly pointed out in the appended claims.

In the drawings:

Fig. 1 is a side elevation of a combined timer and distributor for automobile ignition systems showing my invention as applied to the timer portion thereof. In this illustration some parts are broken away and other parts are in section to show the timer;

Fig. 2 is an enlarged plan view of the timer showing my improved circuit breaker or interrupter with parts of the breaker supporting plate broken away and showing the breaker in open circuit position;

Fig. 3 is a plan view similar to that shown in Fig. 2 but showing the breaker in closed circuit position;

Fig. 4 is an end view taken on line 4-4 of Fig. 2 showing an end view of the breaker, and portions of the cam and rotor;

Figs. 5, 6 and 7 are cross-sections taken respectively on lines 5-5, 6-6, and 1-1 of Fig. 2;

Fig. 8 is a view similar to that shown in Fig. 2, but showing a modification of my invention;

Fig. 9 is a cross-section taken on line 9-9 of Fig. 8;

Fig. 10 is a cross-section taken on line 10-10 of Fig. 8; and

Fig. 11 is a cross-section taken on the line 11-11 of Fig. 8.

In the illustration of one adaptation of my invention, as shown for example in the combined distributor and timer for automobile ignition systems in Fig. 1, the ignition coil 10 is mounted in a housing 11 having an integral casing 12 for housing the circuit breaker generally indicated by numeral 16. The primary terminal is indicated by 18, the usual condenser by 15, the breaker supporting plate by 14, and the rotor or distributor shaft 17.

Contact between the primary circuit of coil 10 and one of the breaker arms 26 is established and maintained through the flexible metallic conductor 21, one end of which is connected to the flexible breaker arm 26 at the support 22 and the other end of which is fixedly connected to the cupped metallic contact 28 carried on the support 29 which is made of electrically non-conductive material and riveted to the breaker supporting plate 14.

The metallic contact 28 is connected to the primary circuit of coil 10 through a resilient coiled conductor 30 one end of which is positioned in the cup of the contact 28.

The interrupter or circuit breaker 16, as herein shown in its preferred embodiment, includes the breaker base plate in the form of a die stamping comprising a flat plate portion 19 having an extended end 20 pivotally mounted on pin 21, three vertically bent integral supports 22, 23, 24, and a vertically and partially laterally angularly disposed integral spring support 25.

The adjacent ends of the primary conductor 21 and the flexible breaker arm 26 are securely held upon the upstanding support 22 by the rivet 31 which extends through a flanged insulating sleeve-like washer 32 and the insulating block 33 both of electrically non-conductive material.

Secured to the outer or movable end of the flexible breaker arm 26 is a shouldered rivet 34. The rivet 34 is movable with the end of arm 26 against the pressure of the compressible coil spring 35 disposed between one of the rivet heads and an insulating block 36 of electrically non-conductive material which is secured by rivet 37 to the upstanding support 22.

The other flexible breaker arm 26 is secured at one end by rivet 38 to the upstanding support 23 through which support 23, pin 21 and breaker supporting plate 14 it is electrically grounded. The opposite or movable end of the breaker arm 26 is resisted in its flexible movement by a coil spring 46 wound about the rivet 41 and positioned between the breaker arm 26 and the upstanding support 25. The rivet 41 is shouldered for stationary mounting upon the support 25 and extends through an opening near the end of the arm 26.

Near their outer ends, the flexible breaker arms 26 and 38 have each secured thereto, at their adjacent or opposing sides, a breaker-point 43 of an arc-resistant alloy or of tungsten.

In order to secure a more perfect ground connection through the breaker, a coiled electrical conductor 44 may be inserted and soldered in the slot of the head of the pivot pin 21 and one end of this conductor 44 soldered to the breaker support extension 28, as at 45.

The flexible breaker arm 26 has preferably removably secured thereto a cam-engaging block 46 of wear-resistant and electrically non-conductive material such as a highly compressed fiber composition. This cam-engaging block 46 is preferably formed with an arcuate face and slotted horizontally, as at 47, to provide a recess for a suitable grease lubricant. A fiber angular member 48 may be securely mounted between the rear face of the block 46 and the arm 26 by the securing screw 49 whereby the free angular end thereof forms a retainer at one end of the block to retain the grease against displacement therefrom.

I have provided novel means for automatically retaining the breaker 16 in proper operative position relatively to the cam 18 whereby the cam-engaging block 46 is positively retained in constant contact with the cam 18 even though the block 46 becomes gradually appreciably worn by the rubbing action of the cam 18.

The means for automatically adjusting the cam-engaging block 46 relatively to the cam 18 consists of a wedge block or member 50 slidably mounted upon rod 51, preferably of rectangular cross-section, supported at one end on the breaker supporting plate 14 and having a cotter pin 52 preventing accidental displacement of the wedge block or member 50 therefrom. The wedge member 50 is constantly urged forwardly by the coil spring 53 so that its angular face 54 is being constantly pressed against the angular face 55 of the upstanding support 25 to thereby move the breaker 16 about its pivot pin 21 with the cam-engaging block 46 into proper cam-engaging position in engagement with the cam 18.

Due to the constant pressure of the spring 53 against the wedge member 50, the breaker unit 16 will be automatically urged toward the cam 18 responsively to the wear of its cam-engaging block 46 although as observed during operation the breaker base member 14 is practically stationary.

The pressure of spring 53 and wedge member 50 will retain the cam-engaging block 46 in engagement with the cam 18 however the pressure exerted by the spring 53 is at all times insufficient to overcome the tension of the breaker arm 26 and the coil spring 35 to cause flexing of the arm 26 to thereby close the circuit between the breaker points 43.

In operation, the lobes of the rotating cam 18 will successively engage the block 46 to cause flexing of the breaker arm 26 against the pres-

sure of coil spring 35 to thereby cause successive engagement of the point 43 of the arm 26 with the point 43 of the breaker arm 38 whereby the circuit will be repeatedly closed and opened during the rotation of the cam 18.

The flexing movement of the arm 26 is such that, in the closing of the circuit through the engaged points 43, the arm 38 will also be flexed against the pressure of its coil spring 40 and during such flexing of the arms 26 and 38 the breaker points 43 will, during their engagement with one another, be moved slightly relatively one to the other to cause a wiping contact therebetween due to the difference in the lengths of the arms 26 and 38.

From the above description and attached drawings it will be readily apparent that I have provided an electric circuit breaker or interrupter which includes the following novel features:

Two flexible breaker-point carrying arms mounted on a common pivoted supporting base plate which base plate is automatically adjustable relatively to the operating cam responsively to the wear of the cam-engaging block mounted on one of the breaker arms.

One of the breaker-point carrying arms is preferably longer than the other one of the breaker arms, and one of the breaker arms is preferably slightly angularly disposed relatively to the other arm to thereby cause a slight wiping movement between the breaker arm points during their circuit closing and opening operations.

The breaker arms are made of a comparatively light-weight flexible metal, both of the breaker arms are slightly flexed during their movement by the cam into closed circuit position, and each of the breaker arms is provided with an auxiliary coil spring at or near its unsecured end to insure smooth operation under high speed cam operation by the elimination through such balanced resiliency of undesirable irregular oscillations of the breaker arms.

In the modified construction of my invention, as illustrated in Figs. 8, 9 and 10, the parts and members which are similar to or like those above-described, and shown in Figs. 1 to 7 inclusive, are indicated by like reference numerals and therefore, a description of these similar or like parts is omitted.

The modified parts and novel features embodied in Figs. 8, 9 and 10, include the following:

The shorter resilient breaker arm 51, which is supported on the upstanding support 23, is arranged to be normally positioned with its free end supported upon the narrow pin-like projection 58 which is formed integrally with the angularly bent strip 59 of soft metal such as, for example, soft brass. The assembly and arrangement is such that this pin-like projection 58 of soft metal of somewhat preferably pointed formation will, in a new breaker arm assembly, support said arm 51 and its breaker point 43 in proper spaced position relatively to the arm 26 and its breaker point 43.

Being of comparatively soft metal, this narrow pointed projection 58 is subjected to repeated engagement by the vibrating end of the arm 51 and is gradually flattened at its pointed end to thereby permit the free end of the arm 51 to progressively assume a normal position closer to the arm 26 due to the pressure of spring 40 which tends to normally maintain the arm 51 seated on the projection 58.

The function of such permissible wear of the projection 58 is to provide means for compensat-

ing the usual amount of wear of the new points 43.

In the modification shown in Figs. 8, 9 and 10, the spring 40 is retained in position between the arm 51 and the upstanding base plate retaining wall 60 in axial alignment with the points 43. The wall 60 is formed integrally with the base plate 19, and is disposed angularly relatively to the base plate integral supports 22, 23 and 24 to constitute an engagement wall for the automatically adjustable wedge member 50.

The spring 40 is held against displacement by the engagement of one of its ends about the headed portion 61 of the point 43 and by the engagement of its opposite end about the stud 62 pressed out of the wall 60. This construction eliminates the rivet 41 shown in Figs. 2, 3 and 5.

As shown in Fig. 8, the cam-engagement block 46 is preferably provided with an arcuate grease retainer 63 consisting of arcuate strip of electrically non-conductive pressed fiber secured within the slot 47 by the block retaining rivet 64. This arcuate retainer 63 will resist displacement of a fibrous grease composition from the slot 47.

I claim:

1. In an electric circuit breaker, the combination with a rotatable cam, of electric circuit interrupting means adapted for actuation by said cam comprising a single movably mounted support, a pair of flexible arms mounted on said support and operatively interposed in an electric circuit, a contact on each of said arms, auxiliary resilient means resisting the flexing of said arms in one direction, said cam being adapted to intermittently flex one of said arms to thereby intermittently move its said contact into contact with the said contact on the other of said arms against the pressure of said resilient means to thereby intermittently close and open the circuit, said support being held in stationary position during the flexing of said one of said arms by said cam, and spring-pressed means for automatically moving and retaining said support in proper adjusted position relatively to said cam.

2. In an automobile ignition circuit interrupter, a rotatable cam, a pair of flexible breaker arms, a contact point carried by each of said arms, said arms being adapted to be intermittently flexed by said cam to intermittently close and open the ignition circuit through said contact points, and a stop for limiting the movement of one of said breaker arms in one direction, said stop being of a comparatively soft material adapted to be progressively flattened by successive impacts of said one of said breaker arms to thereby compensate for the wear of said contact points whereby said contact points will be retained in substantially proper relatively spaced open-circuit position.

3. In an automobile ignition circuit breaker adapted to be actuated by a rotatable cam to intermittently close a normally open ignition circuit, a movable support mounted adjacent said cam, a pair of arms mounted on said movable support and operatively interposed within said ignition circuit, a circuit-closing contact carried by each of said arms, said contacts being, in open-circuit position, slightly axially disaligned and one of said arms being movable by said cam independently of the movement of said support to move its circuit-closing contact into intermittent wiping contact with the circuit-closing contact on the other of said arms, and spring-pressed means urging said movable support toward said cam and preventing opposite movement of said movable support away from said cam whereby one of said

arms is maintained in constant contact with said cam, said support being held in stationary position during the flexing of said one of said arms by said cam, and spring-pressed means for automatically moving and retaining said support in proper adjusted position relatively to said cam.

4. In an automobile ignition circuit interrupter adapted to be actuated by a rotatable cam to intermittently close a normally open ignition circuit, a movable support mounted adjacent said cam, a pair of arms movably mounted on said support and operatively interposed within said ignition circuit, a circuit-closing contact point carried by each of said arms, said arms being movable independently of the movement of the support and independently of one another, a cam-engageable member carried by one of said arms, said member being movable by said cam to thereby oscillate its supporting arm and contact point thereon to cause its contact point to be brought into successive contacts with the contact point on the other of said arms whereby the ignition circuit will be intermittently closed, and automatically adjustable spring-pressed means urging said movable support with said cam-engageable member into constant contact with said cam and preventing opposite movement of said movable support whereby said cam-engageable member is positively retained in constant contact with the cam during the oscillation of its supporting arm. 30

5. In an automobile ignition circuit breaker as embodied in claim 4 and wherein said support is pivotally mounted and wherein said pair of arms each consists of a flexible member rigidly connected at one end to said pivotally mounted support.

6. In an automobile ignition circuit interrupter as embodied in claim 4 and including each of said arms consisting of a flexible member rigidly secured at one end to said movable support, and auxiliary resilient means resisting the flexing of said arms in one direction.

7. In an automobile ignition circuit interrupter adapted to be actuated by a rotatable cam to intermittently close a normally open ignition circuit, a support pivotally mounted adjacent said cam, a pair of resilient arms each rigidly secured at one end thereof to said support, said arms being operatively interposed within said ignition circuit, a contact point carried by each of said arms, a pair of spaced supports on said pivoted support, a coil spring carried on each of said spaced supports, said coil springs resisting the movement of said resilient arms in one direction, a block carried by one of said resilient arms in constant engagement with said cam and said block-carrying arm being oscillatable by the engagement of said cam with said block whereby the contact point on said block-carrying arm is brought into intermittent contact with the contact point on the other of said resilient arms against the pressure of said coil springs, and spring-pressed means urging said pivoted support toward said cam whereby said block is constantly retained in operative contact with said cam.

8. In an automobile ignition circuit interrupter as embodied in claim 7 and including an upstanding wall formed integrally with said pivoted support, and said spring-pressed means comprising a spring-pressed wedge in constant contact with said wall whereby said pivoted support is urged to-

ward said cam to thereby retain said block in constant contact with said cam.

9. In an automobile ignition circuit interrupter as embodied in claim 4 and including a stop for limiting the movement of one of said arms in one direction, said stop being of a comparatively soft material adapted to be progressively flattened by successive impacts of said one of said arms to thereby compensate for the wear of said contact points whereby said contact points will be retained in substantially proper relatively spaced open-circuit position.

10. In an electric circuit breaker as embodied in claim 7 and including said circuit-closing contacts substantially axially aligned, a coil spring resisting the movement of said block-supporting arm in one direction, said other arm having a coil spring axially aligned with its circuit-closing contact resisting its movement in one direction.

11. In an electric circuit interrupter adapted to be actuated by a rotatable cam to intermittently close a normally open circuit, a support pivotally mounted adjacent said cam, a pair of movable arms each supported at one end upon said pivotally mounted support, said arms being operatively interposed within the electric circuit, a circuit closing contact carried by each of said arms, said arms being movable independently of the movement of said support, a cam-engageable member carried by one of said arms, said cam-engageable member being intermittently movable by said cam to thereby intermittently move its supporting arm and circuit closing contact thereon to cause such contact to be brought into successive circuit-closing engagements with the contact on the other of said arms, and spring-pressed means urging said pivotally mounted support with said cam-engageable member into constant contact with said cam, said arm, which supports said cam-engageable member, being movable about a center of movement at its support which is non-coincident with the center of the pivotal movement of said pivotally mounted support whereby said cam-engageable member is adapted to move simultaneously in two non-coincident arcs.

12. In an electric circuit breaker, the combination with a rotatable cam, of electric circuit interrupting means adapted for actuation by said cam comprising a single pivotally mounted support, a pair of flexible arms mounted on said support and operatively interposed in an electric circuit, circuit closing contacts, one on each of said arms, a cam-engageable block fixed on one of said arms, said cam having constant engagement with said block during its rotation whereby said block-supporting arm is intermittently flexed to thereby intermittently move its contact into closed circuit contact with the said contact on the other of said arms, and spring-pressed means for automatically maintaining said pivoted support in operative position wherein said block is positively maintained in constant engagement with said rotatable cam, said pivoted support being automatically movable about its pivot toward said cam responsively to the amount of wear of said block, said spring-pressed means comprising a spring-pressed slidably mounted wedge member in contact with said pivoted support urging said pivoted support toward said cam.

OTTO G. GRIESBACH.
